Primary Examiner—Wallace R. Burke*Assistant Examiner*—Marcus Jackson*Attorney, Agent, or Firm*—Richard B. O'Planick; Lisa B. Riedesel[57] **CLAIM**

The ornamental design for a sign holder, as shown and described.

DESCRIPTION

FIG. 1 is a top plan view of a sign holder showing my new design;

FIG. 2 is a bottom plan view;

FIG. 3 is a front elevational view, the rear elevational view being a mirror image thereof;

FIG. 4 is a side elevational view, the opposite side being a mirror image thereof; and,

FIG. 5 is a perspective view thereof, with the broken line showing for illustrative purposes only and forming no part of the claimed design.
